(57) **CLAIM**

The ornamental design for a roll container substantially as shown and described.

DESCRIPTION

FIG. 1 is a left side, top, and front perspective view of a roll container;

FIG. 2 is a left side, top, and rear perspective view thereof;
FIG. 3 is a left side, bottom, and front perspective view thereof;

FIG. 4 is a front view thereof;

FIG. 5 is a rear view thereof;

FIG. 6 is a left side view thereof;

FIG. 7 is a right side view thereof;

FIG. 8 is a top view thereof; and,

FIG. 9 is a bottom view thereof.

The broken lines shown in the drawings depict portions of the roll container that form no part of the claimed design.
